(57) CLAIM

The ornamental design for a toddler toilet seat, as shown and described.

DESCRIPTION

FIG. 1 is a top, front and right side perspective view of a toddler toilet seat showing my new design;
FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 2;

FIG. 11 is an enlarged view of portion 11 in FIG. 2;

FIG. 12 is an enlarged view of portion 12 in FIG. 3;

FIG. 13 is an enlarged view of portion 13 in FIG. 5;

FIG. 14 is an enlarged view of portion 14 in FIG. 7; and,

FIG. 15 is an enlarged view of portion 15 in FIG. 8.

The evenly dashed broken lines illustrate portions of the toddler toilet seat and form no part of the claimed design. The unevenly dot-dash broken lines define the boundaries of the enlarged view and form no part of the claimed design.

1 Claim, 15 Drawing Sheets
